(57) **CLAIM**

The ornamental design for a bottle, as shown and described.

DESCRIPTION

FIG. 1 illustrates a top perspective view of a bottle according to the present invention;

FIG. 2 illustrates a front side elevational view thereof;

FIG. 3 illustrates a back side elevational view thereof;

FIG. 4 illustrates a right side elevational view thereof;

FIG. 5 illustrates a left side elevational view thereof; and,

FIG. 6 illustrates a top plan view thereof.

The ornamental design that is claimed is shown in solid lines in the drawings. Any broken lines in the drawings depict environmental subject matter only and form no part of the claimed design.
